UNITED STATES PATENT OFFICE.

JAMES F. LINCOLN, OF CLEVELAND OHIO, ASSIGNOR TO THE LINCOLN ELECTRIC COMPANY, OF CLEVELAND, OHIO, A CORPORATION OF OHIO.

FRAME FOR DYNAMO-ELECTRIC MACHINES.

Application filed May 3, 1924. Serial No. 710,840.

- In the construction of motors and other similar dynamo electric machines, the main supporting frame, so far as I am aware, has always heretofore been made of cast iron.
- 5 The object of the present invention is to provide, instead of such a cast iron frame, one that is fabricated out of structural steel shapes, namely, one made of steel angle bars or channels suitably shaped and then welded together to form a unitary rigid frame. As a result, not only have I found it possible to provide a stronger and more dependable construction while at the same time greatly reducing the weight of such frame,
- 10 but the cost is likewise greatly reduced, and owing to the greater modulus of elasticity which such steel structural elements possess over cast iron, consequential advantages are also achieved in other respects.
- 15 To the accomplishment of the foregoing and related ends, the invention, then, consists of the means hereinafter fully described and particularly pointed out in the claims, the annexed drawing and the following description setting forth in detail certain mechanism embodying the invention, such disclosed means constituting, however, but one of various mechanical forms in which the principle of the invention may
- 20 be used.
- 25 In said annexed drawing:—
- 30 Fig. 1 is partly a side elevation and partly a central vertical section of a typical motor wherein my improved construction of frame is incorporated; Fig. 2 is a side elevation and Fig. 3 an end plan view of such frame by itself; Figs. 4 and 5 are transverse sections of such frame taken on the planes indicated by the lines 4—4 and 5—5, Fig. 3, respectively; Fig. 6 is a section corresponding with that of Fig. 4, but showing a modification in construction; and Fig. 7 is a plan view of the straight angle bar from which one of the component parts of such frame is fashioned.
- 35 The only parts in the motor assembly shown in Fig. 1, to which attention need be directed in the present connection, are the stator 1 and the frame 2 from which such stator is supported in proper position about the rotor 3. As best shown in Figs. 2 and 3, the frame 2 includes, along with other parts presently to be mentioned, two similar
- 40 frame rings 4, 4, each of which is made from a straight steel angle bar 5 (see Fig. 7), the one flange 5^a of which is somewhat wider than the other flange 5^b. At the respective ends of the bar, said flange 5^b is beveled as shown at 5^c, so that when the bar is rolled into circular shape, the beveled faces 5^c will contact on a radial line. The weld 6 is preferably effected by means of an electric arc, using an arc pencil of suitable metal to fill in any space that may be left due to imperfect fitting of the beveled faces 5^c of flange 5^b and the juxtaposed end faces of flange 5^a.
- 45 After the frame rings have thus been formed by bending the angle bar to circular shape and welding its ends together, as just described, said rings are secured together in proper transversely, i. e. axially, spaced relation by means of a plurality of transverse bars 7 or 8 having the several different forms and interfitting with said frames in the several different ways illustrated in Figs. 4 and 6, respectively. As shown in the figures just referred to, as well as in Fig. 2, the frames are thus secured together with the flanges 5^a directed inwardly, i. e. towards each other, and in the case of bars 7, the ends thereof are notched to interfit with these flanges, such bars being of the same width as flange 5^b. The bars 8, on the contrary, instead of being thus notched, lie wholly within the flanges 5^a, the inner edge of such bar projecting slightly inwardly beyond the corresponding edges of flanges 5^b. Said bars 7 and 8 constitute cross-tie bars, their ends which thus interfit with the rings 2 being permanently welded to the flanges of the latter, as shown in Figs. 4 and 6 and also in Fig. 3, so that a unitary and substantially rigid structure is formed.
- 50 In addition to thus welding the cross tie bars to the rings 2, I also similarly weld in the angle formed between the flanges 5^a and 5^b of the frame rings, at circumferentially spaced points thereabout, a series of nuts 9 through which pass the bolts 10 that are required to hold in place the plates that compose the stator 1. The latter are further held in place by means of flat rings 11 that are locked against the respective sides of said stator by retaining rings 12 of square cross-section fitting into notches

13 in the inner edges of the bars 7 and 8, all as shown in Fig. 1. Feet 14, on which the machine is designed to rest, are finally welded at suitable oppositely spaced points 5 on the flange 5^a of each ring 4.

10 A frame thus made from structural steel shapes permanently welded together in the fashion described I have found is practically free from the danger of breakage experienced with cast iron, while at the same time it is both stronger and decidedly less bulky than any cast iron frame of equivalent strength. A consequential saving in cost is also achieved for not only, as heretofore 15 pointed out, is a saving effected in weight of metal employed, it being necessary to use only one-third to one-half as many pounds to do the same work, but the steel employed will normally cost less than one-half as much 20 per pound as cast iron. It will be understood, finally, that while I have described the frame rings that enter into my improved frame as being fabricated from steel angle bars, structural steel of other cross-sectional 25 forms may be similarly used with the same or nearly equal advantage.

Other modes of applying the principle of my invention may be employed instead of the one explained, change being made as regards the mechanism or steps herein disclosed, provided the means or steps stated by any of the following claims or the equivalent of such stated means or steps be employed.

30 35 I therefore particularly point out and distinctly claim as my invention:—

1. In a dynamo electric machine, the combination with the annular laminated stator; of a supporting frame therefor, said frame 40 including two end-rings, each made from an elongated structural steel member formed into a circle and having its ends welded together, and cross-tie bars welded at their ends to said rings, respectively, said stator

being secured to the inner faces of said cross-tie bars. 45

2. In a dynamo electric machine, the combination with the annular laminated stator; of a supporting frame therefor, said frame including two end-rings, each made from an 50 elongated structural steel member of angular cross-section formed into a circle and having its ends welded together, and cross-tie bars welded at their ends to said rings, respectively, said stator being secured to the 55 inner faces of said cross-tie bars.

3. In a dynamo electric machine, the combination with the annular laminated stator; of a supporting frame therefor, said frame including two end-rings, each made from 60 a steel angle bar formed into a circle and having its ends welded together with one flange of said bar constituting a cylindrical portion and the other a flat inwardly directed portion of the end-ring, and cross-tie 65 bars lying between such flat portions of the two end-rings and welded at their ends to the latter, respectively, said stator being secured to the inner faces of said cross-tie bars. 70

4. In a dynamo electric machine, the combination with the annular laminated stator; of a supporting frame therefor, said frame including two end-rings, each made from a steel angle bar formed into a circle and having 75 its ends welded together with one flange of said bar constituting a cylindrical portion and the other a flat inwardly directed portion of the end-ring, such cylindrical portions of the two end-rings being directed 80 inwardly, and cross-tie bars lying between such flat portions of the two end rings and welded at their ends to the latter, respectively, said stator being secured to the inner faces of said cross-tie bars. 85

Signed by me, this 1st day of May, 1924.

JAMES F. LINCOLN.
